HANDLE FOR DISPOSABLE MOP

Laird F. Covey, Darien, Conn., and Edmund Greacen, Jr., White Plains, N. Y., assignors, by mesne assignments, to Personal Products Corporation, a corporation of New Jersey

Application June 27, 1950, Serial No. 10,782

Term of patent 14 years

(Cl. D9—2)

To all whom it may concern:

Be it known that we, Laird F. Covey, residing at Darien, in the county of Fairfield, State of Connecticut, and Edmund Greacen, Jr., residing at White Plains, in the county of Westchester, State of New York, both citizens of the United States, have invented a new, original, and ornamental Design for Handle for Disposable Mop, of which the following is a specification, reference being had to the accompanying drawing, forming a part thereof, in which

Fig. 1 is a perspective view of a handle for disposable mop, showing my new design;

Fig. 2 is a front elevational view thereof;

Fig. 3 is a side elevational view thereof;

Fig. 4 is a view of the device shown in Fig. 1 looking at the bottom end of the device;

Fig. 5 is a view of the device shown in Fig. 1 looking at the top end of the device;

Fig. 6 is a horizontal section through line 6—6 of Fig. 2;

Fig. 7 is a horizontal section through line 7—7 of Fig. 2; and

Fig. 8 is a horizontal section through line 8—8 of Fig. 2.

We claim:

The ornamental design for a handle for disposable mop, substantially as shown.

LAIRD F. COVEY.

EDMUND GREACEN, JR.
